(57) **CLAIM**

The ornamental design for a curtain clip, as shown and described.

DESCRIPTION

FIG. 1 is a front perspective view of the curtain clip showing my new design, according to a first embodiment;

FIG. 2 is a rear perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof;

FIG. 8 is a bottom view thereof; and,

FIG. 9 is a front perspective view of the curtain clip, according to a second embodiment.

In the drawings, the broken lines are for the purpose of illustrating environment only and form no part of the claimed design.
